UNITED STATES PATENT OFFICE.

HUGO BREHMER, OF PHILADELPHIA, PENNSYLVANIA, ASSIGNOR TO
WILLIAM C. STEVENSON, OF SAME PLACE.

BINDING BOOKS.

SPECIFICATION forming part of Letters Patent No. 239,927, dated April 12, 1881.

Application filed June 1, 1878.

To all whom it may concern:

Be it known that I, HUGO BREHMER, of the city and county of Philadelphia, and State of Pennsylvania, have invented certain new and useful Improvements in Binding Books; and I do hereby declare the following to be a full, clear, and exact description of the same, reference being had to the accompanying drawings, forming a part of this specification, 10 in which—

Figures 1 and 2 are perspective views of books containing my invention, and Fig. 3 a section of one of them.

Heretofore a number of folded signatures or sections composing a book have been secured together by sewing them onto cords resting in saw-cuts in the backs of said signatures or sections, then applying glue to said backs and cords, and then, before the glue is cold, attaching a strip of woven fabric or paper to said backs, extending partially or entirely throughout the length of said signatures or sections. A number of folded signatures or sections composing a book have also been secured together by attaching them, by stitches or staples passing through their folds, to a strip or strips of closely-woven fabric, and then applying glue to the outside of said strip or strips and the exposed portions of the backs 25 of said signatures or sections. In this latter method the glue could not readily be applied until after the signatures or sections had been attached to said strip or strips, and then did not, as ordinarily applied, permeate the latter and insure a proper juncture of the backs of the signatures or sections to each other and to the said strip or strips.

To obviate the last-named difficulty is the object of my invention; and it consists in the 40 combination, in a book, of a number of folded signatures or sections with a strip or strips of open and sufficiently-strong woven fabric, the signatures or sections being united at their backs to the open fabric and to each other by 45 stitches or wire staples passing through their folds, and the glue, which permeates the open fabric and insures a proper juncture or union

of the backs of said signatures or sections to each other and to said strip or strips.

In carrying out my invention I use a strip 50 or strips of woven fabric, which, while sufficiently strong to withstand the "forwarding" operations, is sufficiently open to allow glue, as ordinarily applied, to permeate it, to which a number of signatures or sections composing 55 a book are attached by stitches or wire staples passing through the folds of said signatures or sections, as shown in the figures of the drawings, by any of the machines or modes in use for accomplishing this end. Glue is then applied to the outside of the strip or strips of open fabric and the backs of the signatures or sections not covered by said fabric, which permeates the said strip or strips and insures 60 a proper juncture or union of the backs of said signatures or sections to each other and to said strip or strips.

It is obvious that the strip or strips of open woven fabric may be of any width desired, depending upon the size of the book, whether 70 its signatures or sections are printed or not, and other circumstances.

In securing together the signatures or sections of printed books, it is desirable to use but one strip of open fabric for each book, 75 which may extend partially or wholly throughout the entire length of the backs of the signatures or sections, as shown in Fig. 1 of the drawings. In securing together the signatures or sections of blank books, it is desirable to 80 use two or more of such strips of open fabric, as shown in Fig. 2 of the drawings. One strip may, however, be used with advantage in any kind of book. After the signatures or sections have been attached to said strip or strips 85 of open fabric and the glue has been applied as described, the side boards may be secured in any suitable and well-known manner.

Instead of glue, any other suitable cement 90 may be employed.

Having thus described my invention, what I claim as new, and desire to secure by Letters Patent, is—

The combination, in a book, of a number of

folded signatures or sections with a strip or strips of open fabric, the signatures or sections being united at their backs to the open fabric and to each other by stitches or staples 5 passing through their folds, and the glue, which permeates the said open fabric and insures a proper juncture or union of said signatures or sections to each other, and to said strip or strips, substantially as set forth.

In testimony whereof I have hereunto set to my hand in the presence of two subscribing witnesses.

HUGO BREHMER.

Witnesses:

M. B. PHILIPP,
H. T. MUNSON.
